UNITED STATES PATENT OFFICE.

FREDERICK HART, OF POUGHKEEPSIE, NEW YORK.

HORSE-POWER REGULATOR.

SPECIFICATION forming part of Letters Patent No. 396,931, dated January 29, 1889.

Application filed January 21, 1888. Serial No. 261,453. (No model.)

To all whom it may concern:

Be it known that I, FREDERICK HART, of Poughkeepsie, in the county of Dutchess and State of New York, (formerly of Reading, in 5 the State of Pennsylvania,) have invented new and useful Improvements in Horse-Power Regulators, of which the following is a specification.

This invention relates to a regulator for 10 that class of horse-powers which are provided with an endless tread or apron upon which the horse or other animal stands, and which is set in motion by the animal, and from which power is transmitted by suitable gearing to 15 a rotating shaft journaled in the frame in which the endless tread is mounted. It is well known that the force which the animal exerts upon the movable tread increases and decreases with the pitch of the tread, so that 20 by raising and lowering either end of the tread the force which the animal exerts and the speed of the driven machinery can be regulated.

The object of my invention is to adjust the 25 pitch or inclination of the tread automatically, so that the speed of the rotating shaft is automatically governed and maintained within certain limits of the desired normal speed, thereby adapting such horse-powers for use 30 as motors in connection with machinery or apparatus which require for successful operation a uniform or nearly uniform motion—as, for instance, centrifugal cream-separators.

My invention consists of the improvements 35 which will be hereinafter fully set forth, and pointed out in the claims.

In the accompanying drawings, consisting 40 of two sheets representing suitable apparatus for practicing my invention, Figure 1 is a side elevation of a horse-power provided with my improved regulator. Fig. 2 is a front elevation of the regulator on an enlarged scale. Fig. 3 is a top plan view of the regulator. Fig. 4 is a rear elevation of the ratchet mechanism 45 of the regulator. Fig. 5 is a vertical longitudinal section in line $x-x$, Fig. 2. Fig. 6 is a vertical longitudinal section in line $y-y$, Fig. 2. Fig. 7 is a cross-section in line $z-z$, Fig. 2, on an enlarged scale. Fig. 8 is a horizontal section of one end of the pinion-shaft 50 and connecting parts. Fig. 9 is a horizontal

section of the sliding collar to which the governor-balls are connected.

Like letters of reference refer to like parts in the several figures.

A represents the frame of the horse-power; 55 a , the bed-timbers thereof; B B, the drums journaled in the frame A and around which the endless tread runs; b , the shaft which is directly driven by the endless tread, and b' 60 the shaft which is geared to the shaft b and to which the main pulley B' is secured. All of these parts may be of any suitable or well-known construction.

The bed-timbers a of the frame rest with 65 their lower rear ends upon the ground or some other suitable support and with their elevated front ends upon the regulator, so that the elevated end of the frame is raised and lowered as may be necessary to maintain the normal 70 speed. It is obvious, however, that the regulator may be arranged under the lower end of the horse-power frame.

C represents the frame of the regulator, consisting of upright side bars, c c , which are 75 preferably curved concentrically with the heel or rear end of the horse-power frame, a top cross-piece, c' , and a bottom cross-piece, c'' , which latter may rest upon a sill, c^3 . The side bars, c , are provided on their rear sides 80 with gear-racks c^4 .

D represents a horizontal shaft arranged transversely in rear of the regulator-frame C and provided with pinions d d , which mesh 85 with the gear-racks c^4 .

E E' represent bearing-frames in which the pinion-shaft D is journaled, and which are provided at their rear ends with plates or shoes e e , upon which the elevated ends of the bed-timbers a are supported, and to which they are secured by bolts e' . The frames E E' extend forwardly on the outer sides of the side bars, c c , and are provided on the front sides of the latter with inwardly-projecting lugs e^2 , which stand opposite the pinions d 90 and prevent the latter from getting out of mesh with the gear-racks. By turning the shaft D in one or the other direction the front end of the horse-power is raised or lowered 95 on the elevator-frame C.

F represents the horizontal governor-shaft, arranged transversely in front of the regu- 100

lator-frame C and journaled in the frames E E'.

5 f represents a pulley secured to the shaft F on the outer side of the bearing-frame E and driven from the main pulley B by a belt, f'.

g represents a worm secured to the shaft F on the inner side of the bearing-frame E and meshing with a worm-wheel, G, which turns upon a stud, g', secured to an arm, g'', extending upwardly from the bearing-frame E, as represented in Fig. 5.

H H represent the governor weights or balls, connected by links h with a collar, h', which is secured to the shaft F between the bearing-frames E E'.

h² represents the links which connect the weights H H with a sliding collar, i, mounted on the shaft F.

i' represents a spring surrounding the shaft 20 F between the sliding collar i and the fixed collar h', and tending to press the former away from the fixed collar and draw the weights toward the shaft F.

J represents a ratchet-shaft arranged longitudinally above the governor-shaft F and journaled in the bearing-frame E, as represented in Fig. 6.

J' is a ratchet-wheel secured to the front end of the shaft J.

30 j is an upwardly-projecting pawl-arm mounted loosely upon the shaft J in rear of the ratchet-wheel J', and connected with the worm-wheel G by a rod, j', so as to receive an oscillatory motion from the rotating worm-wheel.

k k' represent two pawls hung to the upper end of the arm j and projecting therefrom in opposite directions over the face of the ratchet-wheel J', as shown in Fig. 2.

40 L is a curved shield or guard plate, which covers part of the face of the ratchet-wheel underneath the pawls k k', and is mounted loosely upon the hub of the ratchet-wheel J' in front of the arm j. This guard-plate is provided on the under side of the shaft J with an arm, l, which is connected by a rod, l', with the sliding collar i on the governor-shaft F.

m represents a worm secured to the rear end of the ratchet-shaft J, and M is a worm-wheel secured to the pinion-shaft D underneath the worm m and meshing with the latter, so that by turning the ratchet-shaft J in one or the other direction the pinion-shaft D is correspondingly rotated, and the front end

55 of the horse-power is raised or lowered by the pinion d engaging with the gear-racks c'.

N is a pulley secured to the governor-shaft F on the outer side of the bearing-frame E, and from which motion is transmitted to the driven 60 machinery or apparatus either directly or by suitable counter-shafting, as may be desired.

When the governor-shaft F rotates at the normal speed, the governor-weights hold the shield L centrally above the ratchet-shaft J, 65 in which position the shield supports both pawls k k' out of contact with the ratchet-wheel J'. In this position of the ratchet mech-

anism the pawls produce no motion in the ratchet-wheel and the horse-power frame remains stationary at the inclination or pitch at which the normal speed is produced. When the speed of the governor-shaft decreases below the normal speed by a decrease of the motive power, or increase of resistance in the driven machinery, or other causes, the governor-weights approach the governor-shaft, the sliding collar i' is pushed outwardly, thereby swinging the shield L from under the pawl k, as represented in Fig. 2, allowing the pawl k to engage with the ratchet-wheel J'. The pawl k now turns the ratchet-wheel J' in the direction of the arrow in Fig. 2, whereby the shaft J is correspondingly turned. This motion of the ratchet-shaft J is transmitted to the pinion-shaft D through the worm m and worm-wheel M, and causes the front end of the horse-power frame to be raised until the normal speed is again established, when the shield L is returned to its normal position by the governor-balls, lifting the pawl k out of 85 engagement with the ratchet-wheel and stopping the motion of the ratchet-shaft. When the speed of the governor-shaft increases beyond the normal speed, the shield L is swung over in the opposite direction from that above 95 described, thereby allowing the pawl k' to engage with the ratchet-wheel. This pawl turns the wheel J' and shaft J in the opposite direction and causes the front end of the horse-power frame to be lowered until the normal speed is reached, when the pawl k' is lifted out of engagement. The pitch of the worm m is so flat that its frictional contact with the worm-wheel M prevents the pinion-shaft D from running down on the gear-racks except 100 when the worm is rotated in the proper direction by the ratchet-shaft J. The ratchet-wheel J' is provided with a handle for turning the shaft J by hand when desired. In this manner the speed of the governor-shaft is 105 automatically maintained with but slight variations from the desired normal speed, thereby rendering animal-powers of the aforesaid description available for driving machinery and apparatus for which such motors have 110 heretofore not been practicable, owing to the irregularity of the motion produced thereby. When it is not desired to obtain a high rate of speed, the regulating mechanism may be 115 connected directly with the main shaft of the horse-power.

I claim as my invention—

1. The combination, with the vertically-movable horse-power tread, of a stationary frame on which the tread can be raised and lowered to change its inclination, and a centrifugal regulator attached to the tread and moving vertically therewith, whereby the vertical movement of the tread on said frame is automatically controlled, substantially as set forth.

2. The combination, with the vertically-movable horse-power tread, of a stationary frame on which the tread can be raised and

lowered to change its inclination, a worm or screw interposed between the movable tread and the stationary frame, whereby the tread is frictionally held in position on the frame,

5 and a centrifugal regulator whereby the vertical movement of the tread on the frame is automatically controlled, substantially as set forth.

3. The combination, with the regulator-frame provided with gear-racks, of a pinion-shaft provided with pinions meshing with said gear-racks and adapted to be attached to the tread of the horse-power, a governor-shaft which is driven from the horse-power, a 10 governor mounted on said shaft, and a ratchet mechanism controlled by said governor and connected with said pinion-shaft, substantially as set forth.

4. The combination, with the regulator-frame provided with gear-racks, of bearing-frames adapted to be attached to the horse-power tread, a pinion-shaft journaled in said bearing-frames and provided with pinions which mesh with said racks, a governor-shaft 15 journaled in said bearing-frames, a governor attached to said shaft, and a ratchet mechan-

ism mounted on one of said bearing-frames which is geared with the pinion-shaft, controlled by the governor, and actuated from the governor-shaft, substantially as set forth. 30

5. The combination, with the regulator-frame C, provided with gear-racks c' , of the pinion-shaft D, provided with pinions d d , meshing with said gear-racks, bearing-frames E E', provided with plates e e , a governor-shaft, 35 F, provided with a worm, g , a centrifugal governor mounted on said shaft, a worm-wheel, G, mounted on the bearing-frame E, a ratchet-shaft, J, journaled in the bearing-frame E', a ratchet-wheel, J', secured to the shaft J, a 40 shield, L, controlled by the centrifugal governor, a pawl-arm, j, connected with the worm-wheel G, a worm, m, secured to the ratchet-shaft J, and a worm-wheel, M, secured to the pinion-shaft D and meshing with the worm 45 m, substantially as set forth.

Witness my hand this 30th day of December, 1887.

FREDERICK HART.
